DOUBLE RUFFLING MECHANISM FOR SEWING MACHINES

Joseph Gallin, New York, N. Y.

Application August 28, 1953, Serial No. 377,043

1 Claim. (Cl. 112—132)

This invention relates to sewing machines and more particularly to sewing machines with duplex ruffling mechanism whereby tucks are formed in the upper and lower faces of a strip of fabric simultaneously with sewing both tucked surfaces of the strip to an edge portion of a sheet of fabric.

In Patent No. 2,086,013, dated July 6, 1937, and Patent Number 2,086,038, there is disclosed a ruffling mechanism whereby tucks are formed in one edge portion of a strip of fabric concurrently with sewing thereof to a sheet of fabric.

The article produced by the mechanism disclosed in the said patents was such that tucks appeared only on one face of the article, and an object of this invention is to provide improvements whereby both the upper and lower surfaces of the article will have similar tucks.

Specifically, it is desirable to provide a highly simplified lower ruffling mechanism below the work supporting base of the sewing machine to complete the operation of covering the upper as well as the lower face of the body fabric with tucks, and without excessive modifications of the sewing machine frame shown in Patent Numbers 2,086,013 and 2,086,038.

With the above and other objects in view, the invention will be hereinafter more particularly described, and the combination and arrangement of parts will be shown in the accompanying drawings and pointed out in the claim which form part of this specification.

Reference will now be had to the drawings, wherein like numerals of reference designate corresponding parts throughout the several views, in which:

Figure 1 is a front elevation of an upper ruffling sewing machine having lower ruffling mechanism of this invention applied thereto.

Figure 2 is a fragmentary end elevation of the machine shown in Figure 1, one side being broken away for facility in the drafting work.

Figure 3 is a plan view of a work supporting plate, showing a modified needle plate cut away to permit the lower ruffer blade to be moved close to the needles, and showing the lower ruffling blade mounted for movement into the cut away portion of the needle plate.

Figure 4 is a cross-sectional view of a double tucked horizontally positioned U-shaped strip made in accordance with this invention and sewed to the upper and lower faces of a sheet of fabric.

Figure 5 is a view showing a series of lower tucks produced by the mechanism disclosed herewith, the tucks being in the lower surface of a U-shaped strip of fabric.

In the illustrated embodiment of the invention, the numeral 10 indicates a work supporting base of a sewing machine, comprising a base plate 11, two spaced needles 12, and a presser-foot 13, resting on a needle plate 14 secured to the work supporting base 10.

Projecting through the needle-plate 14 is a work advancing feed-dog 15 having actuating mechanism (not

2

shown) but which may be of the usual four-motion type of feeding mechanism.

The feed-dog 15 is opposed by the presser-foot 13 having its shank 16 suitably secured to the lower end of a presser-bar 17 vertically movable in the head of the sewing machine in the usual manner.

The needles 12 are secured in a needle-bar 18 vertically movable in the head of the sewing machine. Co-operating with the needles 12 below the work supporting base 19 is an oscillating looper (not shown). The looper thread interlocks with the needle threads to form two needle lock stitching.

A main shaft 20 is suitably journaled in the base portion of the machine and from which the stitch forming and feeding elements are driven.

The base 11 has an upright tubular standard 22 extending therefrom and having an upper overhanging horizontal arm 23 terminating in a hollow upright head 24.

The presser foot 13 has an independently movable component 26 which is pivoted at 27 and yieldingly urged downward toward the work supporting base by a spring 28, the outer end of the component being upwardly inclined at 29.

The upper ruffling mechanism comprises a rock-shaft 30 which extends horizontally along the front surface of the head 24 and which is supported in bearings 31 suitably secured to the head by screws 32. Fixed to the front end of the rock-shaft 30 is a depending arm 33 to which is pivotally attached at the swinging end on a pin 34, a member 35 carrying an upper ruffer blade 36. The upper ruffling mechanism also comprises a separator plate 37 which is supported by a bracket member 38 secured to the head 24 by screws 39. The blade 36 is tensioned by a spring 40.

Rocking movement is imparted to the upper rock-shaft 30 by means of mechanism which includes an eccentric 46 on the main shaft 20. The connecting rod 47 of the eccentric 46 extends upward within the hollow tubular standard 22 and is pivotally connected at its upper end to one end of an arcuate arm 48.

The arcuate arm 48 is of dovetail cross sectional configuration and has its center of curvature in the axis of the eccentric 46 when the arm is at the end of its upward swing with the upper ruffer blade 36 in its fully advanced position at the needles 12.

The arcuate arm 48 is slidably engaged in a correspondingly shaped slot of a head 52 secured to the rear end of the rock-shaft 30, the slot extending crosswise of the axis of the shaft. A hollow clamp sleeve 53 loose on a screw stud 54 projecting laterally from the head 52 has a bevelled surface to engage the lower bevel of the arm 48.

By means of a nut 57 engaging threads on the stud 54 the sleeve 53 is forced inwardly and thereby operates as a wedge to clamp the arcuate arm 48 in the head 52. Upon loosening the wing nut the arcuate arm 48 may be set in different positions in the slot of the head 52 for the purpose of varying extent of movement imparted to the upper ruffer blade 36.

To facilitate these adjustments, the arcuate arm 48 is provided with graduations for selective registry with an arrow mark on the head 52. A pair of spaced laterally projecting pins 60 on the arcuate arm 48 serve by co-operation with the head 52 to limit the extent to which the arm 48 can be shifted with respect to the head 52.

The arcuate arm 48 projects outward from the point of its attachment to the connecting rod 47 within the machine housing through a vertical slot 61 in the side of the standard 22. The above provide for regulation of the upper rock-shaft 30 from the exterior of the machine, all the above is as shown in Patent No. 2,086,038.

The duplex ruffling sewing machine comprises an improved folder 75 which is supported by a bracket 76 to the work supporting base 10. The folder comprises a plate 77 which forms a support for a strip of fabric.

A folding plate 78 is secured to the supporting plate 77 at the lengthwise edges of the inlet portion of the folder and the folding plate is spaced from the supporting plate and arranged substantially parallel therewith, thus forming a guiding channel 80. The supporting plate 77 extends further outwardly than the folding plate 78. The guiding channel 80 at the receiving end is substantially flat.

Both plates 77 and 78 taper gradually and are bent rearwardly from a point at its receiving end to a point substantially in line with the needles, thus causing the guiding channel 80 to assume a substantially horizontally positioned U-shaped form.

The folding plate 78 is cut away centrally thereof, so as to form an opening 82 through which the fabric may be engaged to assist in threading the strip of fabric into the folder.

As shown in Figure 1, the inner wall 85 defining the U-shaped portion of the channel 80 is directed in a right-angled direction and in line parallel with the line of stitching. The wall 85 is at a considerable distance from the needles.

The edge 86 of the plate 78 defining the U-shaped portion of the channel 80 is spaced away from the wall 85 to provide free exit for the fabric from the channel 80.

It is to be noted that the wall 85 is considerably elongated and converges in substantially U-shaped form towards the needles, and together with a similarly curved supporting wall 87 which is spaced therefrom, provide a U-shaped guiding channel 88 which is much smaller than the guiding channel 80.

The walls 85 and 87 form the delivery end of the folder and terminate slightly in front of the stitch-forming and feeding mechanism of the sewing machine. At the delivery end from the folder, the free side edges of the wall 85 are gradually curved to form folding and guiding scrolls 89 which are carried around the edges 90 of the supporting plate 87.

The supporting plate 87 is cut away centrally thereof, to form an opening 91 through which the strip of fabric may be engaged to assist in threading the fabric through the folder extension 92.

The improvement consists of the lower ruffling mechanism and comprises a rock-shaft 100 extending horizontally along the base 11 and which is supported in spaced bearings 101 secured to the base.

Fixed to the front end of the rock-shaft 100 is an upper arm 102 to which is pivotally attached at the swinging end, a member 103 carrying a ruffler blade 104. The carrier member 103 is connected to the upper end of a tension coil spring 105 which at its lower end engages an adjustable tension arm 106 secured to the upright arm 102 by a clamp screw 107.

The spring 105 holds the front edge 109 of the lower ruffler blade 104 yieldingly in contact with a separator plate 110 which is supported by a bracket member 111 secured to the base portion of the machine. The pressure of the lower ruffler blade 104 toward the separator plate 110 can be varied by regulating the tension of the spring 105, and by adjustment of the tension arm 106.

As shown in Figure 3, the front portion 112 of the needle plate 14 in alignment with the needle holes is removed to permit the further ruffler blade 104 to closely approach the needle holes 113 in the needle plate.

An upright arm 115 is suitably fixed to the rear end of the rock-shaft 100 and has a segmental slot 116. An eccentric 117 is mounted on the main shaft 20, forward of the eccentric 46. A crank arm or connecting rod 118 is mounted on the eccentric 117 and extends through a slot 119 in the front portion of the base 11 and is pivotally connected to the arm 115 by a stud 120 passing through

the slot 116 and suitably arranged to be adjusted longitudinally of the slot 116 and to be clamped in any desired position therealong. This pivotal connection constitutes means for adjusting the movements of the lower ruffler blade 104.

It is to be noted that the eccentrics 46 and 117 are mounted on the main shaft 20 in timed relation to cause simultaneous formation of upper and lower tucks in the fabric strip when it is in the horizontally positioned U-shaped form at the outlet end portion of the folder 75.

The timing arrangement is made possible due to the independent adjustments of the eccentrics 46 and 117. The ruffler blades are in fully advanced position at the needles when both eccentrics are at their maximum throw.

In operation, a main fabric section in flat form and a strip of fabric in U-shaped form are fed to the needles. The main section is fed into and through the open U-shaped extension or discharge portion 92. The strip to be double tucked is passed through inlet and outlet passageways or guiding chambers 80 and 88 inside the folder.

The main fabric section and the U-shaped strip are simultaneously delivered through the folder 75 and are intermittently advanced by the feed dog 15. The upper edge portion of the U-shaped strip and the main fabric section are maintained in separation by a separator plate 37.

By the action of the upper ruffler blade which is constantly reciprocated by the swinging movement of the arm 33 on the rock shaft 30, the upper edge portion of the U-shaped fabric strip is tucked and caught beneath the presser-foot 13, the upper ruffling blade bringing the upper fabric fold each time slightly beyond the needles.

By the action of the lower ruffler blade which is constantly reciprocated by the swinging movement of the arm 102 on the rock shaft 100, the lower edge portion of the U-shaped fabric strip is tucked and caught beneath the presser-foot 13, the lower ruffling blade bringing the lower fabric fold each time slightly beyond the needles.

The folded strip after leaving the folder is directed to the needles 12 which enter the folded strip so as to pass through both folded edges and through the main fabric section.

It is to be noted that the separator or stripping blades 37 and 110 are spaced apart to permit passage of a main fabric section therebetween.

It is to be noted that the upper and lower ruffling blades 36 and 104 are arranged to feed considerably more of the fabric than the feeding done by the feed-dog 15.

The feeding movements of both ruffler blades start when the needles are out of the fabric. The feeding movements of the ruffler blades stop when the needles enter the fabric.

As shown in Figure 3 by shaded lines, the outer edge 125 defining the cut away portion 112 of the needle plate 14 is beveled downward at an angle of about thirty-five degrees in alignment with the needle holes and in angular alignment with the angular position of the lower ruffling blade 104.

As shown in Figure 3, the lower ruffler blade 104 has an elongated slot 126 allowing for adjustment. The blade 104 has a forward serrated edge 127 in which is formed two needle-receiving slots 128.

Figure 4 is a cross-sectional view of a double tucked horizontally positioned U-shaped strip 130 folded around an edge of a sheet of fabric 131 and secured thereto by two rows of stitching 132. The folded strip 130 has upper and lower tucks 133 and 134. The sheet of fabric may be a quilt or other like material.

In accordance with the patent statutes I have described and illustrated the preferred embodiment of my invention, but it will be understood that various changes and modifications can be made therein without departing from the spirit of the invention as defined by the appended claim.

I claim:

In a sewing machine having needles, a work supporting base, a needle plate, upper and lower ruffling and stripping blades and means for actuating said ruffling blades from opposite directions relative to said base to form ruffles on opposite faces of a single, flat and non-folded fabric strip; comprising a two-direction folder fixed to said work supporting base and having a vertical inlet adapted to receive a flat and non-folded strip of fabric in a direction transverse to the line of stitching, said folder having means for folding the upper and lower edges of said strip and for folding said strip into U-shaped form while supported vertically at the longitudinal front edge portion of said base, said folder having means for refolding said folded strip ninety degrees so as to cause 15 said strip to face in direction of the line of stitching, said folder having means for causing said folded strip to leave said folder in direction parallel with the line of stitching and in horizontally positioned U-shaped form, said upper and lower ruffling blades being positioned to form tucks 20 in the upper and lower edge portions of said folded strip, said ruffling blades being resiliently supported in angular relation with said needles, said needle plate having a front portion removed and having a downwardly bevelled front edge portion in alignment with and close to said 25

needles to permit said lower ruffling blade to closely approach said needles, said lower ruffling blade being positioned below said needle plate and reciprocatingly movable toward and away from the same, said ruffling blades 5 being actuated to form tucks in the lower edge portion of said horizontally positioned U-shaped strip simultaneously with the formation of tucks in the upper edge portion of said strip, stripping blades fixedly mounted between said ruffling blades, said stripping blades being spaced apart to permit entrance therebetween for a body fabric for attaching said post-folded double tucked strip to an edge portion of said body fabric.
